UNITED STATES PATENT OFFICE

GRANT HAMMOND, OF NEW HAVEN, CONNECTICUT, ASSIGNOR OF ONE-EIGHTH TO HENRY P. SAGE AND ONE-EIGHTH TO WILLIAM A. MCLEAN, BOTH OF NEW HAVEN, CONNECTICUT

CARBURETOR

Application filed March 29, 1929. Serial No. 351,019.

My invention relates to the class of devices that are employed for mixing fluids to render them combustible, or for other purposes, and an object of my invention, among others, 5 is the production of a device of this type that shall be capable of obtaining its supply of fluids without the aid of agencies other than those required in the normal operation of the apparatus to which the carburetor is attached.

One form of a carburetor embodying my invention, and in the construction and use of which the objects herein set out, as well as others, may be attained, is illustrated in the 15 accompanying drawing, in which—

Figure 1 is a view in lengthwise central section thru my improved carburetor.

Figure 2 is a view in cross section on a 20 plane denoted by the dotted line 2—2 of Figure 1.

Figure 3 is a view in cross section on a plane denoted by the dotted line 3—3 of Figure 1.

While my improved carburetor is not limited in its use to any special type of apparatus, yet as it is particularly adapted for mixing fluids to increase their combustible properties for use in internal combustion engines, the description herein will be applied 30 more particularly to such use of the carburetor.

In the construction and operation of internal combustion engines it has been common practice either to locate the receptacle 35 for the combustible fluid for gravity flow to the carburetor, or, when the receptacle is located below the carburetor, to force the fluid upwardly as by means of vacuum tanks, pumps, or other devices. My improved carburetor is so constructed and arranged that it will by its operation alone obtain the necessary fluid from sources located below its level.

Such carburetor is shown in the accompanying drawing wherein the shell is composed of two sections 3—4 of tubular form and preferably round in cross section, this shell being substantially of uniform diameter as to outside and inside measurements 50 and the two sections being secured together

in any suitable manner, as herein shown, the reduced end of one section being threaded into the counterbored end of the other section. Any suitable means, as set screws 5, may be employed for locking the sections 55 against relative rotation. The section 3 is provided with a flange 6 as a means for securing the device to the engine intake manifold in the usual and well known manner.

A Venturi-tube 7, formed as shown in Figure 1, is fitted to the interior of the section 3 of the shell, this fit being such as to permit movement of said tube under the application of some force.

A needle casing 8 is located within the shell section 3 and has a projection 9 within which the inner threaded end of a nipple 10 is secured. The end of the projection 9 extends into a hole in the tube 7 and abuts against the inner surface of the shell section 3. The 70 projection is of such length as to position the needle casing in the axial center of the opening through the carburetor shell, the nipple having an enlarged end providing a shoulder 75 11 that seats against the bottom of a recess 12 in the outer surface of the section 3 whereby, when the nipple is screwed against its seat, the casing 8 is firmly secured in place in the position shown in Figure 1. The outer end of the nipple is formed to receive a coupling for a pipe extending from a source of 80 fuel supply.

The needle casing 8 is tapered or pointed at its upper end and is provided with a chamber 13 formed by boring inwardly from that end opposite the point. A threaded plug 14 fits the threaded mouth of the chamber 13 and this plug has a tapered hole 15 to receive a needle 16 that is tapered to correspond with and fit said tapered hole. The taper of the 90 hole and needle is very slight. The needle at its inner portion has a sliding fit in the bore of the casing 8, this portion being larger than that portion fitting within the hole in the plug, and grooves 17 are formed extending lengthwise along the outer surface of said enlarged portion to permit free flow of fuel from an inlet passage 18 past the enlarged part of the needle.

A spring 19 seated at one end against the 100

inner end of the chamber 13 and at its opposite end against the inner end of the needle 16 forces the tapered portion of the latter into contact with the tapered hole 15. The 5 plug 14 is provided with a head somewhat larger in diameter than the outside diameter of the casing 8 and the edge of this head is fluted or grooved to permit flow of fuel from a vacuum chamber 20 within a vacuum cup 10 21 secured to the end of the needle 16 and surrounding the end of the casing 8 but with an annular space 22 between the inner surface of the cup and the outer surface of said casing. The outer end of the cup 21 is preferably of semi-spherical shape.

A throttle valve 23 is mounted in the section 4 of the main shell, this valve having a shaft 24 rotatably mounted in opposite sides of the section 4. In the structure herein shown, the 20 valve is secured in any suitable manner in a slot cut through the shaft. A throttle lever 25 is secured to a projecting end of the shaft.

A needle actuator 26 is pivotally mounted on the valve 23 so that its edge is in contact 25 with the curved end of the vacuum cup 21. In the arrangement shown here in this actuator is in the form of a plate pivotally mounted in a slot in a rib 27 extending radially on the valve 23, the sides of the slot in the rib 30 forming a guide for the pivotal movement of the actuator.

A priming pin sleeve 28 is screw threaded to fit a tapped hole through the shaft 24 and a priming pin 29 is mounted for sliding movement in said sleeve, the inner end of the pin being headed for engagement with the needle actuator 26 and also to prevent it from dropping out of the hole in the sleeve. These parts are so arranged that said pin will be 40 in line with the needle 16 when the valve 23 is closed. The end of the sleeve may be flanged and this flange may be knurled to permit easy rotation thereof as by the thumb and finger.

A priming lever 30 in the form of a bell 45 crank is pivotally mounted in a slot in the outer edge of the section 4 of the casing, one arm of the lever underlying the end of the pin 29, as shown in Figure 1 of the drawing, and the other arm of the lever being provided 50 with means for attachment of a connection from a priming device that may be located in any suitable position, as on the dash board of a vehicle.

The parts having been assembled, as herein 55 set forth, and the carburetor installed, with one end bolted to the engine intake manifold, the throttle lever connected to an acceleration device and a fuel feed pipe being connected to the nipple and extending to a fuel feed 60 tank the general operation of the carburetor is as follows:

The throttle being closed, or in its idling position, the engine shaft is rotated in any suitable manner, as by means of a self-start- 65 er. At the same time the lever 30 is operated

as by means of a knob or similar device on the dash of the vehicle in the usual manner. This operation will move the arm of the lever 30 that is in contact with the pin 29 inwardly. This operation moves the pin 29 inward swinging the actuator 26 on its pivot. The curved cam-shaped edge of the actuator being in contact with the vacuum cup 21, the latter is raised, lifting the tapered needle 16 from its seat, thus opening a passage from the 75 vacuum chamber 20 into the fuel supply pipe. The vacuum caused by the pistons in this rotation of the crank shaft will draw fuel from the chamber 20 through the passage in the carburetor and into the chambers in the cylinders, and at the same time fuel will be drawn by the same force from the fuel supply into the chamber 20. It will be noted that the vacuum cup 21 is raised when the needle 16 is moved from its seat and that the 80 cup is lowered when the said needle is moved toward its seat. This movement of the cup with reference to the plug 14 varies the capacity of the vacuum chamber 20 inversely with the variations made in the flow opening 85 through the plug 14 by movement of the needle relative to its seat.

It will have been noted that the operation just described has been effected without opening the throttle 23 and consequently a 90 high vacuum has been set up in the interior of the carburetor that instantly induces a flow of fuel through the pipe line from the supply tank into the inlet passage 18, to the interior of the needle casing 8 along the 100 grooves in the needle and into the vacuum chamber 20. From said chamber the fuel flows through the channels in the head of the screw plug 14 and through the annular space between the vacuum cup and the casing 8. 105

After the engine has been started, as above described, the operation of the carburetor will be the same as in prior devices, with the exception that the fuel supply is directly from the supply tank into the carburetor and 110 not through any auxiliary device.

The relation of the taper of the needle to the curve of the cam 26 will be such that extremely low idling speed and all higher speeds may be maintained with great economy in the use of fuel and smoothness of operation of the engine. 115

With the throttle open, the inrush of air through the Venturi-tube and past the mouth of the vacuum cup 21 is such that an ample 120 supply of fuel is maintained and this is most efficiently vaporized.

After the parts have been installed, as hereinbefore described, with the proper relationship between the curves of the actuator 125 26 and the needle 16 established, proper adjustment may be obtained by turning the regulating or priming pin sleeve 28, as by means of its knurled head, in or out, as may be required. 130

Adjustment of the throttle lever may be had in the usual manner, as by means of an adjusting screw 31, in the end of the lever seated against a pin 32 projecting from the 5 side of the carburetor casing.

I claim:

1. An up flow carburetor including a casing having vertically aligned air inlet and mixture outlet openings, a vacuum member with 10 a vacuum chamber therein located in said casing in the path of a current of air flowing through said casing, means providing a passage from said chamber to a source of fuel supply, means for causing the fuel to change 15 its direction of flow in said chamber below the first mentioned means, a valve to regulate flow of fuel to said chamber, and means for applying force mechanically to said valve to open it.
2. A carburetor including a casing, a vacuum member including a movable vacuum chamber therein located in said casing in the path of a current of air flowing through said casing, means providing a passage from said 20 chamber to a source of fuel supply and including a tapered valve seat, a tapered valve attached to said chamber and fitting said seat to regulate the flow of fuel to said chamber, and means for operating said valve.
3. A carburetor including a casing, a vacuum member including a movable vacuum chamber therein located in said casing in the path of a current of air through said casing, means providing a passage from said chamber to a source of fuel supply, a valve attached to said chamber to regulate flow of fuel to the latter, said valve having longitudinally extending grooves for flow of fuel therealong, and means for operating said 40 valve and moving said chamber.
4. A carburetor including a casing, a vacuum member with a variable capacity vacuum chamber therein located in said casing in the path of a current of air flowing through said casing, means providing a passage from said chamber to a source of fuel supply, a valve to regulate flow of fuel to said chamber, and means for operating said valve by force applied mechanically thereto to open it and to vary the capacity of the vacuum chamber.
5. An up-flow carburetor including a casing having vertically aligned air inlet and mixture outlet openings of equal cross-section, 45 a vacuum member with a vacuum chamber therein located in said casing in the path of a current of air flowing through said casing, there being an uncontrolled opening from said vacuum chamber into said casing, means 50 providing a passage from said chamber to a source of fuel supply, said opening and passage causing the fuel to flow in opposite directions into and out of said chamber, a plug closing the exit opening from said passage 55 into said vacuum chamber, a valve fitting a

valve seat in said plug, and means for actuating said valve.

6. A carburetor including a casing, a movable vacuum member with a vacuum chamber therein located in said casing in the path of a current of air through said casing, a conduit providing a passage from said chamber to a source of fuel supply, said conduit extending into said vacuum member and formed to provide a space between its outer wall and the inner wall of said vacuum member, the capacity of said space being varied by the movement of said chamber, a valve to regulate flow of fuel from said passage into said chamber, and means for moving said member by force applied mechanically thereto to open it.

7. A carburetor including a casing, a movable vacuum cup having a vacuum chamber therein located in said casing in the path of a current of air through said casing, a conduit providing a passage from said chamber to a source of fuel supply, said conduit projecting into the mouth of said cup with a space between the outer surface of the conduit and the inner surface of the cup, the capacity of said space being varied by the movement of said member, a plug closing the exit of said passage into said chamber, a grooved head on said plug fitting the inner surface of said chamber, said plug having an opening therethrough, a valve fitting a valve seat in said opening, and means for operating said valve and moving said member.

8. A carburetor including a casing, a movable vacuum member with a vacuum chamber therein located in said casing in the path of a current of air through said casing, means providing a passage from said chamber to a source of fuel supply, a valve to regulate flow of fuel to said chamber, said valve being secured to said vacuum member for operation thereby, and means for operating said vacuum member.

9. A carburetor including a casing, a detachable valve casing extending longitudinally in the axial center of said carburetor casing, a lateral projection from said valve casing, means passing through the wall of the casing for securing said projection to said carburetor casing, said securing means, projection and valve casing having a passage for flow of fuel from a source of fuel supply, a vacuum member located at one end of said passage and having a vacuum chamber communicating with said passage and with an opening from said chamber into the carburetor casing, a valve to regulate flow of fuel from said passage to said vacuum chamber, and means for operating said valve.

10. A carburetor including a shell, a detachable valve casing with a valve chamber therein and a tapered outlet opening therefrom, a lateral projection from said valve casing, means passing through the wall of the shell

- for securing said projection to said shell to position the valve casing in the shell, said securing means and projection having an inlet passage to said valve chamber, a valve located 5 in said valve chamber, said valve being tapered to fit the tapered outlet from said valve casing, a spring within said valve chamber to force the valve to its seat, and means for operating said valve.
- 10 11. A carburetor including a shell, a Venturi-tube located in said shell, a valve casing extending lengthwise along the axial center of said tube, a lateral projection from said casing, means for securing said projection to said shell, said securing means and projection having an inlet passage to a valve chamber in said casing, a vacuum member having a vacuum chamber to receive fuel from said passage, said vacuum chamber having an opening into 15 said shell, a Venturi-tube surrounding the aforesaid inlet passage, a valve to regulate flow of fuel to said vacuum chamber, and means for actuating said valve.
12. A carburetor including a shell, a vacuum member with a vacuum chamber therein located in said shell in the path of a current of air therethrough, a conduit providing a passage from said chamber to a source of fuel supply, said passage having a tapered outlet 20 into said vacuum chamber, a valve tapered to fit said outlet, and a valve actuator having a curved actuating surface to mechanically apply force to said valve to open it, said surface being co-ordinated with the taper of said valve to effect an economic supply of fuel into said shell.
13. A carburetor including a shell, a movable vacuum member with a vacuum chamber therein located in said shell in the path 25 of a current of air flowing therethrough, and with a passage into said chamber from said shell, a conduit upon which said movable member is mounted providing a passage from said chamber to a source of fuel supply, a valve connected to said member and regulating the flow of fuel to said chamber, a choke valve for the bore through said shell, a valve actuator mounted on said choke valve, and means for operating said actuator.
14. A carburetor including a shell, a vacuum member with a vacuum chamber therein located in said shell in the path of a current of air flowing therethrough, a conduit providing a passage from said chamber to a 30 source of fuel supply, there being an uncontrolled opening from said chamber into said shell which surrounds said conduit, a valve to regulate flow of fuel to said chamber, a choke valve for the passage through said shell, a valve actuator pivotally mounted on said choke valve, and means for operating said choke valve and the actuator thereon.
15. A carburetor including a shell, a vacuum member with a vacuum chamber therein located in said shell in the path of a current 35 of air flowing therethrough, there being an opening from said vacuum chamber into said shell, a conduit providing a passage from said chamber to a source of fuel supply, a valve to regulate flow of fuel to said chamber, a valve actuator for said valve, primary means for operating said actuator, and secondary means for operating said actuator independently of the operation of said primary means.
16. A carburetor including a shell, a vacuum member with a vacuum chamber therein located in said shell in the path of a current of air flowing therethrough, there being an opening from said chamber into said shell, a conduit providing a passage from said chamber to a source of fuel supply, a valve to regulate flow of fuel to said chamber, a valve actuator for said valve, a support for said actuator, means for moving said support to operate said actuator, and means for operating said actuator independently of said support.
17. A carburetor including a shell, a vacuum member with a vacuum chamber therein located in said shell in the path of a current of air flowing therethrough, there being an opening from said chamber into said shell, a conduit providing a passage from said chamber to a source of fuel supply, a valve for said conduit, a throttle valve, an actuator for the conduit valve mounted on said throttle valve, means for operating said actuator independently of the throttle valve and means for moving the throttle valve to operate said actuator.
18. A carburetor including a shell, a vacuum member with a vacuum chamber therein located in said shell in the path of a current of air flowing therethrough, there being an opening from said chamber into said shell, a conduit providing a passage from said chamber to a source of fuel supply, a valve for said conduit, a throttle valve to control flow of fluid through said shell, an actuator for the conduit valve movably mounted on said throttle valve, a priming pin mounted in said throttle valve to engage said actuator, means for operating said throttle pin, and means for operating said throttle valve.
19. A carburetor shell, a throttle valve located at the air intake end of said shell, a valve casing with gasoline intake opening, a valve normally forced towards its seat in said casing, and a cam located between the throttle valve and the valve in said casing and operatively connected with the throttle valve for operation thereby, said cam being also operatively connected with the valve in said casing for mechanical operation thereof to admit gasoline in predetermined proportions to the amount of air admitted to the case by the opening of the throttle valve.
